United States Patent Office.

RALPH S. JENNINGS, OF NEW YORK, N. Y.

Design No. 3,134, dated July 28, 1868.

DESIGN FOR A SHIRT-CUFF.

The Schedule referred to in these Letters Patent and making part of the same.

TO ALL WHOM IT MAY CONCERN:

Be it known that I, RALPH S. JENNINGS, of New York, in the county of New York, and State of New York, have originated and designed a new Pattern for Shirt-Cuffs; and I do hereby declare that the following is a full, clear, and exact description of the construction and operation of the same, reference being had to the annexed drawings, making a part of this specification, and to the letters and figures of reference marked thereon.

The drawing is a representation of my design.

It consists in applying a likeness of General U. S. Grant and Hon. Schuyler Colfax to a shirt-cuff, in the manner and form shown on the drawing.

What I claim as my invention, and desire to secure by Letters Patent, is—

The design for shirt-cuffs, herein set forth and shown.

In testimony that I claim the above, I have hereunto subscribed my name in the presence of two witnesses.

RALPH S. JENNINGS.

Witnesses:

J. B. NONES,
JAMES TAYLOR.
